COMBINED TELEPHONE HAND SET AND STAND

Dieter Blumenau, Stuttgart-Feuerbach, Germany, assignor
to International Standard Electric Corporation, New
York, N.Y., a corporation of Delaware

Filed June 17, 1960, Ser. No. 61,008

Claims priority, application Germany Jan. 22, 1960

Term of patent 14 years

(Cl. D26—14)

Fig. 1

Fig. 2

Fig. 3

FIG. 1 is a front perspective view of a combined telephone hand set and stand, showing my new design;

FIG. 2 is a rear perspective view; and

FIG. 3 is a side perspective view thereof, with the hand set in a different position.

I claim:

The ornamental design for a combined telephone hand set and stand, as shown.
